BARREL STAND

Donald E. Meehan, Stockton, Calif.

Application June 21, 1948, Serial No. 34,221

2 Claims. (Cl. 214—65)

1

This invention relates to barrel carriers.

It is an object of the present invention to provide a barrel stand which is portable and which provides a carrier for a barrel wherein the barrel can be moved from place to place and when so located can be tilted for the purpose of emptying its contents and wherein by the manipulation of the carrier, the barrel can be elevated to a position where it can be tilted and wherein all this may be done without the necessity of having to bodily lift the barrel and place it in position upon the stand, the carrier being moved into engagement with the barrel to make the connection of the barrel therewith while the barrel is in an upright position on the floor.

Other objects of the present invention are to provide a barrel carrier or portable stand for barrels which is of simple construction, easy to manipulate, inexpensive to manufacture and efficient in operation.

For other objects and for a better understanding of the invention, reference may be had to the following detailed description taken in connection with the accompanying drawing, in which

Fig. 1 is a side elevational view of the carrier tilted to receive a barrel which is standing upon end on the floor.

Fig. 2 is a side elevational view of the carrier after the barrel has been picked up.

Fig. 3 is a side elevational view of the carrier when the handles have been detached from their original positions and extended to the side of the barrel, the connection between wheels and frame being lowered.

Fig. 4 is a side elevational view of the carrier with the connection being raised and the wheel frame and the main frame extending parallel to one another.

Fig. 5 is a side elevational view of the carrier serving as a stand and with the barrel tilted to a position whereby its contents may be dispensed and with the handles removed and placed on the frame to extend upwardly and out of the way.

Fig. 6 is a side elevational view of the carrier with the carrier raised upon the wheels to a position of transport.

Fig. 7 is a front elevational view of the carrier and of the barrel supported therein.

Fig. 8 is a top plan view.

Fig. 9 is an enlarged fragmentary and side elevational view of the main frame and of the wheel portion adjustably connected thereto.

Fig. 10 is a fragmentary elevational view of the upper end of the frame at the pivot connection of the barrel therewith.

2

Fig. 11 is a transverse sectional view taken on line 11—11 of Fig. 9.

Fig. 12 is a sectional view, in elevation, taken on line 12—12 of Fig. 9.

Fig. 13 is a fragmentary sectional view taken on line 13—13 of Fig. 10.

Fig. 14 is a sectional view taken on line 14—14 of Fig. 11.

Referring now to the figures, 15 represents a main frame having feet portions or projections 16 extending from the opposite sides of the frame and from a U-shaped member 17 providing the base of the frame. Extending upwardly at the opposite sides of the U-shaped member are side members 18 and 19 uniting at their upper end to support a bearing 21 through which a trunnion 22 of a barrel strap 23 extends. This barrel strap 23 has a plate 24 connected to the same, Fig. 10, in which there is an arcuate slot 26. This plate 24 is secured to the strap 23 through the trunnion 22 by welding, as shown in Fig. 13 at 27. A clamping bolt 28 extends through the plate 24 and secures the plate to the upwardly extending pieces 18 and 19 upon a wing nut 29 being tightened, Fig. 13. The strap 23 is welded to the trunnion 22 at 30 and extending from one strap 23 at one side of the frame to an opposite strap are parallel supporting straps 31 and 32 adapted to support and retain a barrel 33. The barrel is finally secured in the back straps 31 and 32 by wires 35 and 36 having respectively adjustable connections 37 which can be turned or adjusted to lock the barrel in place.

On the bottom piece 17 of the frame 15 and extending upwardly are projections 40 to which are pivotally connected side members 41 having supporting wheel 42 journaled between them. Between the members 41 is a transverse portion 43 over which is extended a latch hook 44 to normally retain the members 41 and the wheel 42 extended to elevate the pivotal connection of the members 41 with the projections 40. The hook 44 is an extension of a rod 45 which is pivotally connected at 46 to a lever 47 which is in turn pivotally connected to base portion 17 at 48. The upper end of the lever 47 has an operating rod 51 connected thereto. This rod extends through an opening 52 in the upright member 19 and has a handle 53. With the rod 51 pulled the hook 44 can be released from the transverse portion 43 whereby to release the wheel members 41 and permit the same to be pivoted.

Pivottally connected to the hook rod 44 is an arm 54 which is normally held down by a spring

55 surrounding its pivotal connection 56. The spring pressed link 54 will also act upon the members 41 carrying the wheel 42 to urge them into a position whereby they will be adapted for engagement of the hook 44 and in a position whereby the members 41 will extend horizontally.

To secure the barrel 33 to the carrier, the rod 51 is pulled to release the wheels 42 so as to buckle the wheel members with respect to the main frame 15 in order that a position such as shown in Fig. 1 may be assumed. Handles 58 at this time will extend through sleeves 61 on the upstanding members 18 as shown in Fig. 1. The handles are pulled down to set the carrier in the position shown in Fig. 1. The straps 31 and 32 will engage the side of the barrel, and the wires 35 and 36 will be tightened therearound. Thereafter, the barrel can be elevated by lifting upwardly on the handles 59 to elevate the barrel and the supporting frame to the position shown in Fig. 2. Thereafter the handles 59 can be removed and extended through the frame pieces 13 and 19 as shown in Fig. 3. The handles then will be in position to effect a lift upon the pivot connection between the wheel members 41 and the frame portion 17 whereby to bring the wheel members and the frame to the position shown in Fig. 4. The frame 17 will thereupon be brought into position whereby its feet projections 16 will lie flush with the floor, as shown in Fig. 4. The carrier will then be set up as a stand. The handles can be returned to extend vertically along the side frame piece 18 as shown in Fig. 5. If it is desired to tilt the barrel in order to empty some of its contents through a spigot 63, wing nut 29 is released and the trunnions 22 of the strap 23 will be pivoted in the bearing 21 so that the barrel may be tilted to the position shown in Fig. 5.

If it is desired to transport the barrel 33 to a new location, the handles 59 are removed from the pieces 18 and extended through pieces 18 and 19 as shown in Fig. 6. The carrier can then be picked up with the barrel and supported on the wheels 42 and the same transported to the new locations, the feet projections 16 having been elevated from the floor.

While various changes may be made in the de-

tail construction, it shall be understood that such changes shall be within the spirit and scope of the present invention as defined by the appended claims.

5 I claim:

1. A barrel carrier comprising a main body portion having a bottom U-shaped member and upstanding side members, strap means adapted to be extended about a barrel journalled on the upstanding side members, wheel devices respectively connected to the main member of the frame and at opposite sides thereof, feet projections on the main frame member, and means for releasably retaining the wheel devices against pivotal adjustment with respect to the main frame portion and for retaining one end of the frame portion in an elevated position, and means for clamping the barrel strap means with the barrel to the upstanding side pieces and against pivotal displacement, said clamping means being releasable to permit the barrel to be tilted to empty some of its contents, handle means releasably connected to the side frame pieces, said side frame pieces having openings for receiving the handle means to extend at different angles therefrom.

2. The invention as in claim 1 wherein said strap means comprises vertically extending straps, other straps adapted to extend partially about the barrel and connected respectively at the ends of the vertical straps and adjustable rods extending from the straps surrounding the barrel and adjustable to retain the barrel in place within the strap means.
